BOLOMETER CONSTRUCTION

Alfred A. Obermaier, Chicago, Ill., assignor to
 Illinois Testing Laboratories, Inc., Chicago, Ill.,
 a corporation of Illinois

Application November 12, 1947, Serial No. 785,240

4 Claims. (Cl. 73—355)

1

My invention relates, generally, to the construction of bolometers, and it has particular relation to ionization type bolometers and methods of operating the same.

Among the objects of my invention are: To vary the number of molecules of a gas available for ionization as a function of temperature; to measure the resultant current flow which is a function of the temperature; to contain the gas in an ionization chamber and to bombard its molecules with alpha particles emitted by radioactive material in the chamber; to increase the sensitivity of the device by employing a radiation receiver in the chamber; to employ a pair of spaced electrodes in the chamber between which a unidirectional electric field is maintained for causing current flow therebetween; and to measure such current flow by thermionic means.

Other objects of my invention will, in part, be obvious and in part appear hereinafter.

My invention is disclosed in the embodiments thereof shown in the accompanying drawing and it comprises the features of construction, combination of elements, arrangement of parts, and method of operation which will be exemplified in the constructions hereinafter set forth and the scope of the application of which will be indicated in the appended claims.

For a more complete understanding of the nature and scope of my invention reference can be had to the following detailed description, taken together with the accompanying drawing, in which:

Figure 1 is a detailed sectional view taken along the line 1—1 of Figure 2 and illustrating somewhat diagrammatically a preferred form of bolometer construction;

Figure 2 is a detail sectional view taken along the line 2—2 of Figure 1;

Figure 3 illustrates, diagrammatically, the bolometer construction shown in Figures 1 and 2 and also how the current flow therethrough as a function of temperature can be measured by thermionic means;

Figure 4 shows a curve which demonstrates the operating characteristics of the bolometer shown in the preceding figures; and

Figure 5 illustrates, diagrammatically, an alternate bolometer construction and how it may be connected to a measuring circuit.

Referring now particularly to Figures 1 and 2 of the drawing, it will be observed that the reference character 10 designates, generally, a bolometer of the ionization type constructed in

2

accordance with my invention. The bolometer 10 includes an ionization chamber 11 that may be formed of quartz or it may be formed of metal with a window of quartz for receiving radiant energy. The ionization chamber 11 is evacuated and then filled with a volatile insulating liquid 12, such as carbon tetrachloride. For a given temperature the space 13 above the surface of the liquid 12 contains a certain number of free molecules or vapor in equilibrium with the surface of the liquid. As the temperature inside of the ionization chamber 11 increases the number of free molecules will be correspondingly increased. This increase in density is accompanied by an increase in pressure within the ionization chamber 11. Thus the number of molecules in the space 13 above the liquid 12 or the pressure within the ionization chamber 13 is a function of the temperature.

With a view to utilizing this change for making a temperature measurement, provision is made for ionizing the molecules of the gas in the space 13 by bombarding the same with alpha particles emitted from a foil of radioactive material 14 also located within the ionization chamber 11. The number of ionized molecules of the gas in the space 13 also is a function of the temperature.

As shown in the drawing, an electrode or grid 15 and an electrode or plate 16 are positioned in insulated spaced relation within the ionization chamber 11 and, as will be described hereinafter, they are maintained at a predetermined relative unidirectional potential so that an electric field is generated therebetween. When the potential of the plate 16 is higher than that of the grid 15, the ionized molecules are attracted to the former and thus a flow of current takes place therebetween. The current flow is a function of the number of ionized molecules which, in turn, is a function of the temperature within the ionization chamber 11.

The bolometer 10 is made more sensitive by the provision within the chamber 11 of a radiation receiver 17 in the form of a thin strip of copper or gold covered with lamp black. The radiation receiver 17 readily absorbs the radiant energy falling thereon and effects a corresponding increase in temperature of the gas in the space 13.

The radiant energy to which the radiation receiver 17 is subjected is indicated by the arrow 18 in Figure 3. With the bolometer 10 constructed as described, the radiant energy thus received by the radiation receiver 17 increases

the number of molecules available for ionization in the space 13 in direct proportion to the amount of energy received. By measuring the current flow between the electrodes 15 and 16, it is possible to obtain an indication of the amount of radiant energy received. Accordingly, the electrodes 15 and 16 are connected to terminals 19 and 20, respectively, between which there is maintained a difference of unidirectional potential such as a potential of 150 volts.

When the electrodes 15 and 16 have the unidirectional potential applied thereto as illustrated in Figure 3, the current flow therebetween is proportional to the temperature within the chamber 11 which in turn is proportional to the vapor density therein. The relationship between the vapor density within the ionization chamber 11 and the current flowing between the electrodes 15 and 16 is indicated by the curve 21 in Figure 4. Tests have shown that the slope of the curve 21 is constant regardless of the ambient temperature.

In order to measure the current flow between the electrodes 15 and 16, the electrometer 22 of the thermionic type in Figure 3 may be used. The electrometer 22 includes a pair of electric valves 23 each of which includes an anode 23a, a control grid 23g, and a hot cathode 23c. The cathodes 23c may be interconnected by a resistor 24 whose midpoint is connected through a resistor 25 to ground and to negative terminal 19. The electrode 15 may be connected to one of the grids 23g, as shown, and through a resistor 26 to a point along a voltage dividing resistor 27, connected between the terminals 19 and 20, where a biasing voltage of about 65 volts is applied to the grids 23g.

The null method of measurement is employed and for this purpose a galvanometer 29 having a pointer 30 and a scale 31 may be employed. The galvanometer 29 is connected between anode resistors 32, as illustrated. At a given temperature the system is adjusted by a variable resistor 33 so that the pointer 30 is positioned at the zero point relative to the scale 31. Now as radiant energy is received by the radiation receiver 17 in the bolometer 10, the number of molecules available for ionization by the radioactive material 14 is increased correspondingly and there is a corresponding increase in the current flow between the electrodes 15 and 16. The pointer 30 moves up the scale 31 which may be calibrated in units of pressure or temperature as desired.

Another embodiment of my invention is shown in Figure 5. The bolometer 10', there shown, is similar to the bolometer 10 except for the omission of the electrode or grid 15 and the positioning of the radiation receiver 17 to one side of the ionization chamber 11. The plate or anode 16 is connected directly to one of the grids 23g of the electrometer 22 while the radioactive material 14 is ungrounded. When so arranged and connected, the bolometer 10' functions as a Faraday cage with the charge thereof being a function of the radiant energy applied to the receiver 17. This effects a corresponding control of the conductivity of the associated valve 23 which is reflected in the indication provided by the galvanometer 29.

Since certain further changes can be made in the foregoing constructions and methods and different embodiments of the invention can be made without departing from the spirit and scope thereof, it is intended that all matter shown in the accompanying drawing and described here-

inbefore shall be interpreted as illustrative and not in a limiting sense.

I claim as my invention:

1. Apparatus of the class described comprising, in combination, an evacuated container having a wall through which radiant energy is adapted to be received into the container and containing a volatile liquid from which free molecules of vapor are liberated by the temperature within the container and in amount which changes according to changes in temperature, radioactive material within the container and operable to ionize, independently of the radiant energy, the free molecules of vapor liberated from the volatile liquid, an electrical circuit having a source of electric energy therefor and including therein an electrode disposed within said container and having current flow developed therein in response to the ionized molecules of vapor and in amount which is a function of the number of ionized molecules, and an electrical indicating instrument in circuit with said electrode for indicating by the amount of current flow in said circuit the amount of radiant energy received into said container.

2. Apparatus according to claim 1 wherein the electrode is in the form of a plate element, and wherein there is a grid element disposed within the container in spaced relation to said plate element and connected to said electrical circuit for generation of an electrical field between the grid element and said plate element.

3. Apparatus of the class described comprising, in combination, an evacuated container containing a volatile liquid from which free molecules of vapor are liberated by the temperature within the container and in amount which changes according to changes in temperature, said container having a wall through which radiant energy may enter the container, radioactive material within the container and operable to ionize, independently of the radiant energy, the free molecules of vapor liberated from the volatile liquid, an electric circuit including therein an electrode disposed within said container and having a current flow developed therein in response to the ionized molecules of vapor, an electrical indicating instrument in said circuit, and a radiation receiver disposed within the container and of a character to absorb radiant energy entering the container to effect a corresponding increase in temperature therein, whereby to increase the sensitivity of the device.

4. Apparatus of the class described comprising, in combination, an evacuated container containing a volatile liquid from which free molecules of vapor are liberated by the temperature within the container and in amount which changes according to changes in temperature, said container having a wall through which radiant energy may enter the container, radioactive material within the container and operable to ionize, independently of the radiant energy, the free molecules of vapor liberated from the volatile liquid, an electrical circuit including therein an electrode disposed within said container and having current flow developed therein in response to the ionized molecules of vapor, an electrical indicating instrument in said circuit, said electrode being in the form of a plate element, a grid element disposed within the container in spaced relation to said plate element and connected to said electrical circuit for generation of an electrical field between the grid element and said plate element, and a radiation receiver disposed

within the container and of a character to absorb radiant energy entering the container to effect a corresponding increase in temperature therein, whereby to increase the sensitivity of the device.

ALFRED A. OBERMAIER.
